UNITED STATES PATENT OFFICE

WILLIAM GIVONE, OF EAST PATERSON, AND HERBERT JAHN, OF GARFIELD,
NEW JERSEY

PLAYING CARD HOLDER

Application filed July 8, 1930. Serial No. 466,436.

This invention has for its object to provide a holder for playing cards or the like in which the player can conveniently place his cards and have them held securely and yet so as to be easily withdrawable therefrom and uniformly spaced. In carrying out the invention we employ a series of stiff laminated leaves of preferably conforming shape and pivoted together so that when the series is extended fan-fashion the cards may be fitted between the leaves, the series having gages for the gaging of the cards in offset or fan-like arrangement. Further, in the preferred construction the series of leaves has a series of stops, in one form herein set forth consisting of a flexible device threaded through them and in two other forms consisting of abutting portions formed on the leaves.

In the drawings,

Figs. 1 to 5 illustrate the invention in its first form;

Fig. 1 being a front elevation, with the cards in place;

Fig. 2 a rear elevation with the cards removed;

Fig. 3 a front elevation of one of the leaves;

Fig. 4 a section on line 4—4, Fig. 1; and

Fig. 5 a view of a spacer;

Figs. 6 to 10 illustrate another form,

Fig. 6 being a front elevation thereof;

Fig. 7 a similar elevation of two of the leaves, open;

Figs. 8 and 9 showing such two leaves, separated; and

Fig. 10 showing, detached, the stops for these leaves; and

Figs. 11 to 16 showing the third form,

Fig. 11 being a front elevation thereof;

Figs. 12 and 13 views of two of its leaves, separated;

Figs. 14 and 15 being a radial section and a section on line 15—15, Fig. 11; and

Fig. 16 showing a spacer for this form.

The leaves may be formed of any suitable stiff sheet material, as sheet celluloid. Their form is not particularly material excepting that they are preferably elongated and have their pivoting ends narrower than their free ends.

Figs. 1 to 5: The leaves 1 are pivoted on a stud which, as shown in Fig. 4, is a two-part rivet, one part 2 of which is driven with a snug telescopic fit into the other 3, the heads of the rivet holding the leaves, and washers or spacers 4 alternating with them, clamped fairly tightly together. The leaves have at their free ends projecting tabs 5 all bent off in the same direction out of the respective planes of the leaves and these form gages against which the edges of the cards 6 inserted between the leaves may be made by the player to abut. Each leaf is limited to back and forth movement around the pivot a definite distance relatively to its neighbor thus: The leaves all have a pair of holes 7 arranged the same distance from the corresponding side edges of the leaves and through their holes is extended a cord or other flexible device 8 in such manner that the cord is rebent in passing from one hole to the other in each leaf, such rebend preventing slippage of the cord in the leaf; the portions of the cord linking the leaves together are all of equal length, to wit, so that there will be no slack therein when the series of leaves is fully collapsed and squarely superimposed on each other, with said portions then of course bent around their edges. Thereby these linking portions, when the series is fully extended, cause all the leaves to be offset with respect to each other equal distances, and in the collapsing operation they limit the collapsing movement to that arrangement in which the leaves are all squarely superimposed on each other. Of course the tabs or gages are all placed in the same relative positions on the leaves so that with the leaves, when the series is extended, equally offset from each other the tabs will be also equally offset.

In Figs. 2 and 3 the leaves are shown with portions 1a pressed out of their planes and acting to augment the grip of the leaves on the cards.

In Figs. 6 to 10 the leaves 9 and their tabs 10 may be substantially the same as already described, but a different means for limiting their extending and collapsing movement of the leaves is shown. Each leaf has its pivotal portion in effect thickened and formed

at one face thereof with a straight shoulder 11 which is in a diameter of the pivot and on the other side with an obtuse angular shoulder 12, said shoulders facing relatively oppositely. In the series, the thickened portion forming the straight shoulder of any one leaf is in the same plane with the thickened portion forming the obtuse shoulder of the next adjoining leaf. Consequently any one leaf 10 can move pivotally relatively to the other the limited distance represented by the dotted angle α in Fig. 7. The thickened shoulder-forming portions may be provided as shown by gluing pieces 13 of sheet material to the 15 leaves.

Figs. 11 to 16: Here the leaves 14 and tabs 15 are again the same except for the means for limiting the pivotal movement of the leaves. Each leaf in an arc concentric with 20 its pivot has a single lug 16 projecting from one face thereof and a pair of lugs 17, spaced greater than the width of lug 16, projecting from its other face; these may be produced by 25 pressing out the material of the leaf. The leaves are assembled so that the single lug of any one leaf is on the face thereof adjoining that face of the neighboring leaf having the two lugs. Where the lugs are formed by a pressure operation it is obvious that without spacing means a single lug would catch in the opening, as 18, formed by the single lug of the neighboring leaf. Hence it is preferable to provide a spacer or washer 19 having 30 an arcuate slot 20 receiving the lugs of both leaves and which prevents this but leaves a single lug of one leaf in the plane of and thus adapted to coact with the two lugs of the next leaf to limit the pivotal 35 movement of the leaves.

40 Having thus fully described our invention what we claim is:

1. A device for holding cards or the like comprising a laminated series of leaves to receive the cards between them and pivoted together 45 so that each leaf is movable independently of the others in its own plane, said series having a series of means to limit the pivotal movement of the leaves, each with respect to the neighboring leaf, in the direction to extend the series.

2. A device for holding cards or the like comprising a laminated series of leaves to receive the cards between them and pivoted together 55 so that each leaf is movable independently of the others in its own plane, said series having a series of means to limit the pivotal movement of the leaves, each with respect to the neighboring leaf, in the direction to collapse the leaves.

60 3. A device for holding cards or the like comprising a laminated series of leaves to receive the cards between them and pivoted together 65 so that each leaf is movable independently of the others in its own plane, said series having a series of means to limit the piv-

otal movement of the leaves, each with respect to the neighboring leaf, in either direction.

4. A device for holding cards or the like comprising a laminated series of leaves to receive the cards between them and pivoted together 70 so that each leaf is movable independently of the others in its own plane, said series having a series of means to limit the pivotal movement of the leaves, each with respect to the neighboring leaf, in the direction to extend the series and the leaves having card gages projecting all from the corresponding faces of the leaves.

5. A device for holding cards or the like 80 comprising a laminated series of leaves to receive the cards between them and pivoted together so that each leaf is movable independently of the others in its own plane, said series having a series of means to limit the 85 pivotal movement of the leaves, each with respect to the neighboring leaf, in the direction to extend the series and the leaves having projecting tabs bent off in the same direction and forming card gages, 90

6. A device for holding cards or the like comprising a laminated series of leaves to receive the cards between them and pivoted together 95 so that each leaf is movable independently of the others in its own plane, the leaves having card gages projecting all from the corresponding faces of the leaves.

7. A device for holding cards or the like comprising a laminated series of leaves to receive the cards between them and pivoted together 100 so that each leaf is movable independently of the others in its own plane, the leaves having projecting tabs bent off in the same direction and forming card gages.

In testimony whereof we affix our signatures.

WILLIAM GIVONE.
HERBERT JAHN.
